ELECTRIC JUMPER AND CONTACT

Thomas E. Curtis, Hampton, Ga., assignor to
 Southern States Equipment Corporation, a cor-
 poration of Georgia

Application July 23, 1949, Serial No. 106,345

4 Claims. (Cl. 339—9)

1

This invention relates to electric circuit-interrupting devices such as switches, fuses, and the like, particularly those for outdoor use on high-voltage circuits.

An object of this invention is to provide jumper means whereby the mechanical functioning of a device such as an electric switch may be tested while the device is in service.

A further object is to provide means whereby a high-voltage fuse cartridge may be removed for inspection or replacement without interruption of the load supplied by the fuse. Heretofore it has been necessary to obtain clearance on the fuse in order to inspect the fuse element for possible deterioration after long service. Frequently alternative sources of power are not available, and it has been necessary to interrupt the service, causing considerable inconvenience and expense.

The jumper would also be useful for maintaining service while automatic switching equipment was tested. Such switching systems are often quite complex and sometimes involve load-break switches. These systems frequently supply service for long periods of time without operating mechanically, and yet are called upon for dependable operation under extreme conditions whenever necessary. This jumper would provide a means of maintaining service while the switching equipment was operated for testing purposes.

Another object is to provide such a jumper which is simple and economical in construction, and which is adaptable for use on any circuit-interrupting device of the general types used on high-voltage electric systems. It is the well established practice to mount all such high voltage circuit interrupting devices upon insulator units which conform to established standard specifications. Such an insulator unit includes a flat topped metal cap affixed to the top of the porcelain and the cap is drilled and threaded to receive bolts which are used to secure the current carrying members to the top of the insulator. The size of the bolts and the diameter of the bolt circle is specified for each size of insulator unit. See Patents Nos. 1,560,998, 1,635,049, 2,231,992, 2,521,826.

Another object is to provide new members which can readily be attached to existing apparatus, thereby providing supporting means for the jumper.

Figures 1 and 2 show respectively the upper part and the lower part of one form of jumper embodying the features of this invention, the hole 14 being shown in each figure, and Figure 1

2

being partially in section; Figure 3 is a partial view to the same scale showing the top of one form of insulating switch stick which could be used to operate the device shown in Figures 1 and 2. The switch stick and a jumper supported thereon are together designated as the jumper assembly. Figures 4, 5, and 6 drawn to a smaller scale show successive steps in the operation of the jumper shown in Figures 1 and 2 in conjunction with a high-voltage circuit-interrupting device such as a switch, fuse, or the like; Figure 7 drawn to a larger scale is a plan view of one type of metallic stationary contact which is adapted for mounting between the terminals of a circuit-interrupting device and their respective insulating supports, and which is co-operable with a jumper shown in Figures 1 and 2; Figure 8 to the same scale is a side elevation of the member shown in Figure 7.

20 Referring to Figure 1, a jumper 1 has an upper jumper contact 2 fastened to a tubular housing 3 by means of screws 4, 4. The upper contact 2 may be made in any convenient shape, but preferably it is made annular. At the lower extremity of the upper contact 2 is a hole 5 which is inside the cover or housing 3. One end of a helical extension spring 6 is hooked to hole 5, and the other end is hooked to an eye 7 formed in end of a link 8. A similar eye 9 in the other end of link 8 is hooked to a hole 10 in the lower jumper contact 11. A shoulder 12 of lower contact 11 bears against the end of the cover 3 when end members 2 and 11 are free. The relative lengths of the cover 3, the spring 6, and the link 8 are such that the shoulder 12 on lower contact 11 is held rather loosely against the end of the cover or tubular housing 3 when the jumper contacts 2 and 11 are free.

40 A flexible metallic conductor 13 provides a low resistance electrical path between jumper contacts 2 and 11. One end of the conductor 13 is fastened to upper jumper contact 2, preferably by soldering. Conductor 13 passes inside the coils of spring 6, makes several turns around link 8, and is fastened to lower jumper contact 11 in a manner similar to the junction with upper end member 2. The purpose of coiling conductor 13 into several turns about link 8 is to provide for axial movement of lower end member 11 with respect to upper end member 12 while the two are joined by conductor 13. It is apparent that the above described arrangement is readily adaptable for use under any of a large number of different voltage conditions. In almost every 50 application of the jumper, the terminals to be

bridged are disposed vertically, one above the other, or with one terminal at a higher level than the other so that all or an appreciable portion of the weight of the parts is taken by the upper terminal. A jumper for high voltage application must have a longer cover or housing 3, a longer link 8, and possibly a longer conductor 13 than does a jumper for a lower voltage application. Since any increase in the length of link 8 and of conductor 13 would not materially increase the loading of spring 6, and since the vertical component of the weight of the relatively heavy cover 3 is taken by the upper contact member 2, the loading of spring 6 and the resulting contact pressure at contact 11 is substantially independent of the voltage rating or physical size of the jumper. Thus by the invention substantially uniform contact pressure is achieved for all voltage ratings and this highly desirable result is achieved with a minimum of special parts. Stated otherwise, jumpers of all voltage ratings use the same parts except for the housing or cover 3, the link 8 and possibly the conductor 13 although it is possible that a standard length for the conductor 13 could be found which would be satisfactory for all voltages, since any surplus length for low voltage jumpers probably could be coiled within the housing cover 3 in any suitable manner if desired.

Lower jumper contact 11 may be made in any of several possible forms. A simple ring would be satisfactory, but the arrangement shown is preferred. A large ring 14 is formed in lower jumper contact 11 near the shoulder 12. A hollow cylinder 15, having a length several times greater than its diameter joins the ring 14 opposite shoulder 12, such that the hollow cylinder 15 is co-axial with cover 3. Ring 14 and cylinder 15 are integral parts of lower jumper contact 11.

One type of insulating switch stick in common use is shown in Figure 3. To an insulating rod 16 is fastened a head 17, consisting of a cylindrical body 18 with a cone-shaped tip 19, and having a laterally extending finger 20 at right angles to the cylindrical body 18, and spaced some distance from the conical tip 19. The form of invention here shown uses a socket designed for use with an insulating stick having such a head. The open end of the hollow cylinder 15 has a curved slot 21 designed for engagement with the laterally extending finger 20 of the insulating stick head 17 when the cylindrical body 18 is inserted in the hollow cylinder 15 in a bayonet-type joint. The entire Jumper 1 shown in Figures 1 and 2 can thus be supported by the switch stick, and this jumper assembly is all in alignment, so it is easily handled by the insulating rod 16.

One use of the jumper 1 shown in Figures 1 and 2 in conjunction with a high-voltage circuit-interrupting device is shown in Figures 4, 5, and 6. Referring to Figure 4, switch stick head 17 is engaged with lower contact 11, and the jumper 1 is raised into position so that the upper contact 2 is engaged with a laterally extending stationary contact 22 which may be part of one terminal 23 of a circuit-interrupting device 24 such as a switch, fuse, or the like. Referring to Figure 5, with the upper end member 2 of the jumper 1 engaged with stationary contact 22, an axial pull is applied to the insulating rod 16, thus extending spring 6 and increasing the spacing between upper contact 2 and lower contact 11. Simultaneously lower contact 11 is moved laterally by means of insulating rod 16 so that lower contact 11 is engaged with another stationary contact 25

5 on a second terminal 26 of circuit interrupting device 24, contact 25 being similar in form to contact 22. The normal length of the jumper 1 is purposely made shorter than the spacing between stationary contacts 22 and 25 so that when jumper contacts 2 and 11 are engaged respectively with stationary contacts 22 and 25 the jumper contacts 2 and 11 are held in firm contact with their respective stationary contacts 22 and 25 by the tension of spring 6. After the jumper 1 is thus engaged, as shown in Figure 6, the head 17 of the switch stick may be rotated and then withdrawn from engagement with lower contact 11. An electrical path of adequate capacity is thereby established between terminals 23 and 26 of circuit-interrupting device 24, so that the bridging means 27, which may be a switch blade, fuse cartridge, or the like, may be removed without affecting the current which may be flowing through the device between terminals 23 and 26. And with the long switch stick removed, the compact jumper is not in the way of anything else.

20 After bridging means 27 is restored to engagement with terminals 23 and 26, the jumper 1 may be removed by the reverse of the procedure described above. The head 17 on the switch stick is inserted in the open end of the hollow cylinder 15 and engaged by a combined thrusting and 25 rotary movement. An axial pull is applied to the rod 16 combined with a lateral movement, to disengage lower jumper contact 11 from stationary contact 25. The jumper 1 can then be lifted from engagement with stationary contact 22, thus restoring the circuit-interrupting device 24 to its 30 normal operating condition.

35 Stationary contacts 22 and 25 can be made as integral parts of terminals 23 and 26 respectively. A more satisfactory method would be to make 40 separate contact members 28, as shown in Figures 7 and 8, adapted for mounting between terminals 23 and 26 and their respective insulating supports 29 and 30. These members preferably are made with their hook portions in the 45 same plane as the flat plate portion and are symmetrical so that identical parts could be used with both terminals 23 and 26, and they could be provided with various sets of holes conforming to various standardized drillings for insulator caps so that identical parts could be attached to any circuit-interrupting device on which it might be desirable to use the jumper 1. It will be observed that the hook has a surface which is disposed tangentially relative to the point on the periphery of the flat plate portion from which the hook projects. This constructional feature makes it possible to preserve the normal spacing between the terminals on which two of the hooked contacts are mounted and also avoids sharp points which could provide surfaces from which corona would discharge. By arranging the projections as shown in the drawing, a jumper of minimum length and weight can be used.

45 The jumper 1 alternatively can be used in conjunction with a pair of insulators which are adjacent to but not identical with the insulators supporting the fuse, switch, or other device which is to be by-passed by means of the jumper.

50 Since the spacing between terminals of circuit-interrupting devices of a given voltage rating have become more or less standardized throughout the industry, various jumpers 1, as shown in Figures 1 and 2, could be made, each to fit devices of a particular voltage rating. Contacts 2 and 55 11 and spring 6 could be identical for any voltage

rating, and various length assemblies could be constructed by varying the lengths of cover 3, link 8, and conductor 13.

I claim:

1. As an article of manufacture for use as a hooked contact in association with an electrical terminal, a unitary contact member comprising a flat plate having a substantially circular periphery and a solid midportion and formed with a series of perforations disposed concentrically relative to the periphery of the plate, and a short hook projecting from one part of the periphery of the plate, said hook having a surface thereof disposed tangentially of said one part of the periphery of the plate.

2. As an article of manufacture for use as a hooked electrical contact attachable to a terminal-supporting insulator unit by insertion between the terminal and its supporting insulator unit, a unitary contact consisting of a thin flat plate having a curved periphery and a solid midportion and with a relatively short hooked contact projecting laterally from one portion of the periphery of the said plate, said hooked contact being disposed in substantially the same plane as said plate and a surface of said hooked contact being tangential relative to said one portion of the periphery of said plate.

3. A jumper for interconnecting an upper electric terminal with a lower electric terminal, 30 said jumper comprising a first contact engageable with the upper terminal, a second contact electrically connected with said first contact, a tubular housing of insulating material, said first contact being affixed to one end of said housing and said second contact being disposed at the other end of said housing in axially slideable relationship thereto and with its lower end portion projecting axially from said housing and having a cavity therein constructed to form a 40 temporary operative connection with a switch stick and also formed to engage the lower terminal, said housing being supported by said first contact and the upper terminal when said contacts are in operative engagement with said 45 terminals, a tension spring disposed in said hous-

ing with one end thereof connected to one of said contacts, and a link disposed in said housing with one end thereof connected to the other end of said spring and with the other end thereof connected to the other of said contacts, said spring and said link being effective to bias said contacts toward each other.

4. A jumper for interconnecting a pair of spaced electric terminals, said jumper comprising a tubular housing, a first contact disposed at one end of said housing and being engageable with one of said terminals, a second contact disposed at the other end of said housing in axially slideable relation thereto and with at least a portion of said contact being outside of said housing at all times, said portion of said second contact being engageable with the other of said terminals and having a shoulder engageable with the end of said housing to determine the minimum spacing between said contacts, said portion of said second contact also being formed with a cavity therein to receive and form a temporary operative connection with one end of a switch stick, means for biasing said contacts toward each other, and means for electrically interconnecting said contacts.
